UNITED STATES PATENT OFFICE.

KATHERINE COKER DALTON, OF WASHINGTON, DISTRICT OF COLUMBIA.

DESIGN FOR A MILITARY CLOAK AND SKIRT.

58,551.

Specification for Design.

Patented Aug. 2, 1921.

Application filed May 24, 1918. Serial No. 236,434. Term of patent 3½ years.

To all whom it may concern:

Be it known that I, KATHERINE COKER DALTON, a citizen of the United States, residing at Washington, in the District of Columbia, have invented a new, original, and ornamental Design for a Military Cloak and Skirt, of which the following is a specification, reference being had to the accompanying drawing, forming part thereof.

The figure is a perspective view of a military cloak and skirt, showing my new design.

I claim:

The ornamental design for a military cloak and skirt, as shown.

KATHERINE COKER DALTON.
